TOOTHBRUSH HOLDER

David Beilock, New York, N. Y.

Application March 21, 1945, Serial No. 583,997

2 Claims. (Cl. 312—112.5)

1

The object of the present invention is to provide a toothbrush holder, particularly adapted for plastic manufacture, and which may be used as a wall insert for bathrooms, as to one form of the invention.

The holder comprises a casing and a sliding brush holder adapted to be moved outwardly to expose the brushes, the holder being of special form. The holder is provided with a three-point sliding support within the casing, the arrangement being such that it is adequately held when moved outwardly to expose the brushes, and will be free from undue friction and disarrangement in its backward movement.

The invention will be described with reference to the accompanying drawings in which—

Figure 1 is a sectional elevation of my device taken on the line 1—1 of Figure 2;

Figure 2 is a front elevation, partly broken away;

Figure 3 is a horizontal section taken on the line 3—3 of Figure 2;

Figure 4 is a view in elevation showing the holder associated with an underlying cavity block, certain members being shown in dotted lines.

In its general use, my holder will be sunk into the wall and below it will be provided a cavity of sufficient length for reception of the lower handle portions of a plurality of toothbrushes. Thus, in Figure 4, I have shown a cavity block at 1 which will be open at the top and front to receive the handles of the brushes 2.

The casing may be of unitary plastic formation, comprising a top wall 3, side walls 4, and horizontal flange members 5. Depending from the top wall 3, at the center thereof, is an enlarged area 6 which serves as an aligning guide for a rearwardly projecting slide bar 7, carried by the cover member 8 of the sliding toothbrush carrier. The said front wall has integrally connected therewith a horizontal tray 8x formed with any suitable number of cavities, as at 9, for the brushes 2, and the tray at its upper surface surrounding each cavity may be counter-sunk in conformity with the bristle areas of the brushes, for better holding thereof. Also, the center of the tray may have a seat as at 10 for holding a container, as of an antiseptic or deodorizing composition.

Molded as an integral part of the front wall, in the present embodiment, is a pull handle 11, which may form part of the decorative design, as indicated more particularly in Figure 2.

It will be noted from Figure 1 that the front wall 8 of the toothbrush carrier is formed with a depending area 8xx adapted to cover the front

2

edges of the flange members 5. It will also be noted that the slide bar carries, towards its rear end, a stud 7x which will limit the outward movement of the toothbrush carrier through contact with the rear face of depending enlargement 6.

The structure, as shown in Figures 1 to 3 inclusive, is adapted to be inserted into a wall, as, for example, in substitution of a tile, the cover of the toothbrush carrier serving as a decorative continuation of the tile facing. In such case, a cavity will be provided below the device for reception of the lower handle areas of the brushes. As indicated in Figure 4, this cavity is preferably faced with a hollow block open at its front and top, and as indicated at 1.

The combination of the flanges 5 and the upper and centrally disposed guide provided by the apertured depending enlargement 6, serves to give adequate supporting means for the toothbrush carrier, and, at the same time, enables easy movement of the carrier, with a minimum friction and no jamming, and this with a formation which enables the use of simple molding dies for the plastic employed. In practice, the stud 7x is depressed into a receiving aperture provided in the slide bar 7, after the carrier is inserted in the casing, the apertures in the tray giving sufficient clearance for this purpose.

Having described my invention, what I claim and desire to secure by Letters Patent is as follows:

1. A toothbrush holder comprising a casing having side walls, a rear wall, and a top wall, the casing being of integral construction, and the top wall having a centrally located depending thickened area formed with a horizontal guide aperture the walls of which afford supporting means, a toothbrush carrier having a front wall carrying near its top a slide bar entering the said aperture of the casing and supported by the walls of the said horizontal guide aperture, said front wall also being provided near its base with a tray apertured for the reception of toothbrushes, said tray being projected rearwardly of the front wall, the tray and slide bar being integral with the front wall, said slide bar slidably engaging the top wall of the casing in the movement of the carrier relatively to the casing.

2. A toothbrush holder adapted to be mounted within a wall cavity and consisting of a rectangular casing having side walls, a rear wall and a horizontal top wall, the casing also being formed with opposed inwardly projecting flanges at its base, and with an area depending from its top

wall and centrally thereof said area being formed with a horizontal guide aperture, a toothbrush holder mounted within the casing, said holder consisting of a vertical front wall having centrally and integrally therewith a rearwardly projecting horizontal guide and supporting bar adapted to enter said guide aperture and to rest upon the base wall thereof in a plurality of positions of the front wall relatively to the casing, said front wall also having a rearwardly projecting tray apertured to receive toothbrushes; the sides of the tray normally resting upon the said flanges of the casing and being slidable relatively thereto.

DAVID BELLOCK.
